WASHING MACHINE

Sidney S. Holland, Sandusky, Ohio, assignor to
The Apex Electrical Manufacturing Company,
Cleveland, Ohio, a corporation of Ohio

Application April 21, 1937, Serial No. 138,128

2 Claims. (Cl. 68—132)

This invention relates to a laundry machine and, in particular, to a small portable domestic washing machine, and the gearing or operating mechanism provided therefor.

Present invention has for its objects: the provision of a small portable domestic washing machine which is light in weight and which is of simple and inexpensive construction; the provision of a machine of the type described in which the cover of the washing compartment also constitutes a housing or enclosure for the operating mechanism of the machine; and the provision of a generally simplified form of washing machine mechanism including novel means for effecting the lubrication of the operating elements of the mechanism over extended periods of time without requiring any attention on the part of the operator.

These and other objects in the invention will become more apparent and better understood after consideration has been given to the following detailed description of the invention taken in connection with the drawings which show, merely by way of illustration, structure adapted for carrying out the objects of the invention.

In the drawings, Figure 1 is a side elevational view, partly in section, of a washing machine illustrating one form of the invention; Figure 2 is a plan view of the top of the machine shown in Figure 1; Figure 3 is an enlarged plan view looking down on the operating mechanism of the machine with the cover of the mechanism housing removed; Figure 4 is a sectional view taken on line 4—4, Figure 3; Figure 5 is an enlarged detail sectional view of the upper bearing of the agitator shaft; Figure 6 is an enlarged plan view of the underside of the agitator; Figure 7 is a sectional view taken on line 7—7, Figure 3; Figure 8 is a sectional view taken on line 8—8, Figure 3; Figure 9 is a detail sectional view taken on line 9—9, Figure 3; and Figure 10 is a detail sectional view of a modified form of structure for supporting operating mechanism of the machine upon its removal from the tub.

The washing machine illustrated in the drawings is of light weight and portable construction and it is particularly adapted for use in apartments and small homes which are not provided with a laundry room. Because of its smallness and portability, the washer may be used in the kitchen or in the bathroom and when not in use, it may be stored in a closet or in any other convenient place.

Referring to Figure 1 of the drawings, the washing machine shown therein comprises a tub or container 1 for clothes and washing fluid. The tub 1 is preferably of a unitary construction. Its top edge is turned over at 1a and an annular ring or corrugation 1b is formed in the sidewall of the tub a slight distance below its upper edge.

The tub 1 constitutes a supporting base for the operating mechanism of the machine which is carried by the ring 1b of the tub. A pair of handles 2, 2 attached to the side of the tub are provided for handling the tub and the machine. A ring or corrugation 1d is formed in the sidewall of the tub 1 to indicate the proper water level.

The operating mechanism of the machine is mounted within a housing 3 having a removable cover 4 with a perforated portion 4a which cooperate with perforations 5 in the sidewall of the housing to permit a circulation of air through the housing. Handles 6, 6 are provided for handling the housing 3 and the operating mechanism within it. The housing 3 has a bottom 7, provided with annular ribs 8 and 8a for the purpose of reinforcing and stiffening the same. Legs 3a are welded or otherwise attached to the side of the housing for supporting the same upon its removal from the tub.

An agitator comprising a base part 10, a hub part 10a and blades 11a, 11b and 11c, is suspended beneath the bottom 7 of the housing 3 by means 25 of a shaft 12 received in the hub part 10a of the agitator. The shaft 12 is journaled in a suitable bearing 13 attached to the housing bottom by any suitable means such as a nut 14. An oil-retaining, fibrous washer 13a encircles the shaft 12 above the bearing 13 for the purpose of lubricating the same. The fibrous washer 13a is held in place on the shaft 12 by means of a washer 13b and a pin 13c.

Within the housing 3 there is located a motor 35 15 for driving the shaft 12 and the associated agitator through suitable mechanism which will be described in detail presently. The motor is connected to a source of current supply by means of a cable or cord 16, the same being insulated from the side wall of the housing 3 by means of an electrically non-conducting washer or sleeve 17.

The motor 15 is provided with an armature shaft 18 which is connected to one end of a flexible shaft or tube 20 by means of a cotter pin 21. The other end of the flexible shaft is connected to a worm shaft 22 by means of another cotter pin 23. The worm shaft 22 is journaled in suitable bearings in an oil-retaining gear case 24 having a cover part 24a. A worm 50 25 rigid with the shaft 22 is located inside such gear case.

The worm is adapted for meshing engagement with a worm gear 26 secured to a shaft 28 by 55 means of a pin 30. Upper and lower bearings 31 and 32 are provided in the gear case 24 and its cover 24a for the worm gear shaft 28. The worm gear shaft projects through the cover of the gear case where it is attached to one end 60 of a crank member 33 by means of a pin 34. The

other end of the crank member carries a bearing pin 35 and this element is fastened to the crank by means of a pin 36.

Lubricant may be supplied to the gear case by means of a pipe fitting 37 having a removable filler plug 38 which may be provided with an air vent hole 40, as is shown in Figure 3. The crank pin 35 is journaled in one end of a pitman 41. The other end of the pitman is arranged to receive a bearing pin 42 which is attached at one end to a crank arm 43. The other end of this crank arm is fastened by means of a pin 44 to the agitator shaft 12.

The upper end of the bearing pin 35 is provided with a washer 35a which may be held in place on the pin by means of a cotter pin 35b. The bearing pin 42 is provided at its upper end with a washer 42a which may be held in place by means of a cotter pin 42b. The washers 35a and 42a serve to hold the pitman in place on the bearing pins 35 and 42.

The gear case cover 24a is provided with a pair of arms 45 and 46, the ends of which are adapted for receiving bolts or threaded hooks 47 and 48 respectively, by means of which the gear case may be secured to supporting bars 50 and 51 respectively, which are secured to the housing 3 internally thereof. The gear case cover 24a is also provided with a third extending arm 52 terminating in a cross bar 53, the ends of which are adapted to receive bolts or threaded hooks 54 and 55, by means of which the cross bar may be bolted to the supporting bars 50 and 51 respectively.

A centrally apertured cup-shaped member 56 is formed intermediate the ends of the cross bar 53. This member provides an upper bearing 57 for the shaft 12 and it also provides a lubricant-receiving cavity 58 which communicates by means of a duct 60 with the agitator shaft and in this manner supplies lubricant to the same.

The ends 61 and 62 of the pitman 41 are also arranged with similar lubricant-retaining cavities, as is clearly shown in Figure 4, so that lubricant may be supplied to the bearing pins 35 and 42. In the end 61 of the pitman, the bearing for the pin 35 is indicated by the numeral 62. A lubricant-retaining cavity 63 surrounds this bearing and communication between the cavity 63 and the bearing pin 35 is effected by means of the duct 64.

The end 62 of the pitman is of substantially similar construction to the end just described and in this manner the bearing pins 35 and 42 are supplied with lubricant at all times. In the use of this device, it is intended to use a relatively thick grease so that the lubricant-receiving cavities when once filled, will serve to lubricate their bearings for a relatively long time. The same result could be achieved by packing the cavities about the bearings with an oil soaked, fibrous material.

The motor 15 is surrounded by a band formed from upper and lower halves 65 and 66 respectively. The opposite ends of the bands are joined together by any suitable means, such as, for example, the screws 67. Threaded hooks or bolts 68 and 70 are provided to clamp the motor-supporting band to the supporting bars 50 and 51. A sound-deadening, vibration absorbing element, as for example, a rubber band 71 is provided at each of the points where the bolts 67, 68, 54,

55, 68 and 70 engage the supporting bars 50 and 51.

In the use of the machine, the tub 1 is first charged with fluid and clothes so that the fluid level is at or near the ring or corrugation 1d of the tub. When the motor is operated, the agitator is oscillated about its axis, agitating the fluid and clothes in the tub and in this manner, the washing operation is effected.

The upper portion of the tub 1 closely embraces the lower part of the housing 3 in a readily detachable manner so as to prevent the escape of washing fluid at the junction of the tub and housing during the operation of the machine while at the same time permitting the housing to be readily separated from the tub.

At the termination of the washing operation, the mechanism and its housing may be lifted from the tub by means of the handles 6, 8 and placed to one side of the machine on its supporting legs. The clothes may now be removed from the tub 1 for rinsing and wringing after which another batch of clothes may be placed in the machine.

If desired, supporting legs 3b may be attached to the bottom 1 of the housing 3 and arranged so that they occupy a position closely adjacent to the inside surface of the sidewalls of the tub 1 when the housing is in its operative position. In the use of this arrangement which is illustrated in detail in Figure 10 of the drawings, the channeled side of the legs would be reversed so as to face radially outwardly and thus present substantially smooth, vertically disposed rubbing projections along the sidewall of the tub for the purpose of enhancing the washing action of the machine.

Having thus described my invention what I claim is:

1. A washing machine comprising a washing tub, a cover therefor including a compartment provided with power means to drive an agitator, a motor for said power means eccentrically arranged in said compartment, an agitator depending from the under side of said cover into the washing tub and adapted to wash clothes therein, a plurality of supports depending from said cover, said supports being radially spaced from each other to describe a circle having a diameter exceeding the diameter of said tub and arranged to embrace the side walls thereof, said supports having an axial extent exceeding the axial extent of said agitator, whereby the cover in its entirety may be supported on a surface in upright position upon removal from the washing tub.

2. A portable washing machine comprising a tub, a combined cover and power unit mounted on said tub, said unit including a compartment to house an agitator drive mechanism and a motor eccentrically arranged in the compartment, an agitator depending from the under side of said unit and adapted to extend downwardly into said tub, spaced supporting legs carried by said unit depending downwardly therefrom to embrace the outer walls of the tub and frictionally secure said unit to the tub, said supporting legs terminating in a plane beneath the plane of the lower portions of said agitator, whereby the unit in its entirety may be supported in a stable position on a flat surface upon removal of the unit from the tub.

SIDNEY S. HOLLAND.
